UNITED STATES PATENT OFFICE.

ALBERT H. DE VOE, OF WESTFIELD, NEW JERSEY, ASSIGNOR TO THE SINGER
MANUFACTURING COMPANY, A CORPORATION OF NEW JERSEY.

POWER-STAND FOR SEWING-MACHINES.

1,347,840.

Specification of Letters Patent.

Patented July 27, 1920.

Application filed February 8, 1917. Serial No. 147,296.

To all whom it may concern:

Be it known that I, ALBERT H. DE VOE, a citizen of the United States, residing at Westfield, in the county of Union and State 5 of New Jersey, have invented certain new and useful Improvements in Power-Stands for Sewing-Machines, of which the following is a specification, reference being had therein to the accompanying drawings.

10 This invention relates to an improvement in power-stands for sewing machines and has for certain of its objects to provide a power-stand of this class which will occupy a minimum of floor space, which shall insure 15 convenience in the operation of the machine and facilitate the handling of the work, and which shall increase the capacity of the machine in its accommodation of various kinds of work, reduce the noise of 20 operation of the sewing mechanism, provide safeguards against fire and insure against injury of the operator through contact with exposed moving parts.

In its preferred embodiment, the invention 25 consists in a power-stand comprising a unit or a series of connected units each comprising a column sustaining at its head bearings in which is journaled a power-shaft and sustaining a plurality of power- 30 transmitters connected with the respective sewing machines sustained by rigid supporting shelves extending laterally in different directions from said column intermediate its head and foot and provided with seats to 35 accommodate the bases of the respective sewing machines.

The sewing machines are preferably connected with their respective power-transmitters by means of belts passing over idler-pulleys 40 mounted in swinging housings sustained by the transmitter-frames and spring-retracted to produce the requisite tension upon the belts. The transmitters are preferably controlled by treadles disposed at the foot of the column which is 45 preferably hollow so as to house therein the vertical connections between such treadles and the respective transmitters.

As the sewing machine supporting shelves 50 are comparatively narrow so that the sustaining column may act as a barrier to prevent the tilting of the machine backward upon one edge to expose the parts beneath the bed-plate, means are preferably pro-

vided for shifting such edge of the machine 55 bed-plate at such time forward or away from the column so as to maintain the body of the machine in substantial register with the seats of its supporting shelf and thereby enable it to be tilted backwardly toward 60 the column sufficiently for access to its parts beneath the bed-plate for purposes of inspection, cleaning, oiling, &c.

Further constructive features, as well as 65 the details of construction will be understood by a reference to the accompanying drawings, in which—

Figure 1 is a side elevation of a power-stand constructed in accordance with the present improvement; and Figs. 1^a and 1^b 70 are enlarged elevations, partly in section, representing certain details of the driving means through which the power-shaft is actuated from the source of power. Fig. 2 is an end elevation of the power-stand. Fig. 75 75 3 is an enlarged vertical section of one of the units of the power-stand, Fig. 4 is a plan of the floor-plate for the column and Fig. 5 a section, on the line 5—5 of Fig. 4, of the base of the column and the floor- 80 plate. Fig. 6 is a partial sectional elevation and Fig. 7 a similar end elevation of a pair of power-transmitters sustained by one of the columns, and Fig. 8 a perspective view representing parts of the transmitter. 85

Fig. 9 is a sectional plan of the stand represented in Fig. 1, the section being taken above the shelves. Fig. 10 is an enlarged plan view of one of the machine- 90 supporting shelves, Fig. 11 a transverse section of said shelf, and Fig. 12 a perspective view, upon a still larger scale, representing the pivotal support upon which the sewing machine bed-plate is shifted to facilitate tilting for exposure of the parts beneath the same. Fig. 13 is a detail perspective view representing a part of the connection of a treadle with its respective power-transmitter. Fig. 14 is a perspective view of a portion of one of the transmitter-frames. Fig. 15 is a detached view of one of the transmission-belt housings. Fig. 16 is a perspective view of a lateral rest for a sliding work-box, and Fig. 17 100 105 105 is a detail elevation representing an overhead spool-rack with its supporting means. Fig. 18 is an enlarged perspective view

showing in detail a portion of the spool-rack. Fig. 19 is a perspective view of one of the detachable drip-pans sustained beneath the sewing machine bed-plates. Fig. 20 is a transverse sectional elevation of the head of one of the columns and the transmitter-frame sustained thereby. Figs. 21 and 22 are elevations showing, respectively, in side and edge view the preferred form 5 of belt-housing sustaining idler-pulleys for the belt connecting a sewing machine with its respective power-transmitter.

As represented in the drawings, each unit of the power-stand comprises a hollow column or standard 1 having its base flared to form a hollow flange 2 which is formed with bosses 3 in which are tapped the adjusting screws 4 having lock-nuts 5.

The base of the column rests upon the 10 raised central portion 6 of a floor-plate having depressed and apertured lateral seats 7 entered by fastening bolts 8 and an outer flange 9 secured to the floor by lag screws 10. The arched portion 6 has a central elongated aperture 11 having at one end the enlargement 12 adapted to receive the head of a bolt 13 whose shank extends upwardly through the aperture 11 and through an aperture in the cross-member 14 formed in 15 the lower portion of the column 1, the threaded upper end of the bolt 13 being provided with the nut 15 which is accessible through one of the lateral openings 16 of the column. The portion 6 of the floor-plate is shown provided with a series of 20 raised seats 17 surrounding the aperture 11 to receive the thrust of the adjusting screws 4 by means of which the column may be lined up, to compensate for any unevenness 25 or lack of true of the floor.

The columns 1 are shown provided upon opposite sides intermediate their ends with the lugs or projections 18 affording vertical seats to which are secured by bolts 19 flanges 20 from which extend laterally the sewing machine supporting shelves 21 each formed with an aperture 22 to receive a sewing machine base or bed-plate *a* which is adapted to rest upon the corner lugs 23; these shelves being formed as flat plates with 25 depending stiffening ribs or flanges 21'. The sewing machine supporting shelves are preferably provided each with a bed-plate receiving aperture having corner lugs of suitable form to accommodate the bed-plates 30 or bases of the types of machines which they are designed to sustain; and certain of them are preferably further provided with movable supporting means to facilitate 35 the turning of the machine for exposure of parts beneath the bed-plate.

To facilitate the tilting of the sewing machine from operative position, as indicated in full lines in Fig. 11, to the dotted line 40 position of said figure, the shelf is provided

with depending bearings in which is journaled below and intermediate the side edges of the opening 22 a rock-shaft 24 having fixed thereon the longitudinally spaced backwardly and upwardly extending arms 70 25 having forked extremities in which are pivotally mounted by means of the fulcrum-pins 26 the blocks 27 carrying the split pins 28 entering the usual sockets in the rearward edge of the sewing machine bed-plate. 75 Secured upon said rock-shaft near one end is a hand-lever 29 formed adjacent its hub with a slotted segment plate 30.

The segmental slot 30' of the plate 30 is entered by the clamp-screw 31 passing 80 through a bearing boss 32 of the shelf 21 and having its head 33 provided with a cross-bar 34 for turning the same. The inner portion of the screw 31 enters a nut 35 which is embraced and restrained from turning 85 therewith by means of flanges 36 extending from the inner face of a washer having oppositely projecting wings 37 entering the slot 30' of the segment plate 30. The segment plate may obviously be clamped by 90 means of the screw 31 against the adjacent end of the bearing boss 32 to normally hold the rock-shaft 24 against turning and thus maintain the rearward edge of the sewing machine bed-plate in operative position. 95

The front edge of the bed-plate may obviously be similarly maintained seated upon its respective corner lugs 23 by means of a common form of fastening device comprising a clamp-bolt 38 having at one end a 100 laterally extending head 39 resting upon the bed-plate and upon the threaded opposite end a wing-nut 40 seated upon a suitable part of the table 21.

As represented in Figs. 3 and 19, the shelf 105 21 may be provided with a detachable drip-pan 41 having its end walls extended upwardly to form hooked lugs 42 adapted to rest upon the rock-shaft 24, the front side being formed with a forked lateral lug 43 entered by the bolt 38 and clamped against the lower edge of one of the shelf flanges 21' by means of the nut 40. The nut 40 may be turned to loosen the grip of the head 39 upon the sewing machine bed-plate without 110 disturbing the drip-pan, but the latter may be withdrawn by removal of the nut 40 so that the pan may be tilted downwardly preparatory to detachment from the supporting shaft 24.

In order to tilt the sewing machine backward, as represented in dotted lines in Fig. 11, to expose the parts beneath the bed-plate, the clamp-bolt 38 may be loosened and turned to disengage it from the bed-plate, and the machine swung backwardly, the lever 29, previously unclamped by turning the bolt 31, being at the same time thrust downwardly to throw the supporting arms 125 25 forwardly across the shaft 24.

In this position, the machine remains above and substantially in register with its normal operative position upon its respective supporting shelf, the arm *b* resting 5 against the column 1 or against a post 44 which may be provided for the purpose, as represented in dotted lines in Fig. 11. Under such condition, the center of gravity 10 of the sewing machine lies between the pivotal supporting pins 26 and the more remote seats 23, and thus has no tendency to falling from this position through loss of balance or jarring or other means, while presenting the parts beneath the bed-plate easily accessible 15 to the operator.

Journalized in suitable bearings beneath the shelf 21 is a cross rock-shaft 45 having at its forward end a normally depending knee-lever 45' provided with the knee-plate 46 (Fig. 11), the rock-shaft being provided with the usual thrust-plate or lug 47 (Fig. 10) adapted to engage a part of the sewing machine, such as a lifting rod for the presser-bar. One of the depending flanges 25 21' of the shelf is formed with a lateral notch or recess, as indicated in Figs. 10 and 11, into which one edge of the plate 46 will snap by a slight springing of the lever 45' when swung upwardly so as to maintain the 30 knee-lever in upper inoperative position.

As represented in Figs. 1, 2 and 9, each of the columns 1 is provided upon opposite sides with a bearing 48 in which is rigidly secured a laterally extending rail 49 to which 35 are slidably fitted the hooks or inverted stirrups 50 extending from the adjacent upper edge of a sheet-metal work-box 51, the adjacent side of which rests against the shoe 52 having its shank 53 secured in a suitable lateral boss in the lower portion of the 40 column 1. As shown particularly at the left in Fig. 9, each work-box normally occupies a position mainly below and in the rear of its machine supporting shelf, so that the 45 finished work naturally falls therein without special attention upon the part of the operator; but may be readily drawn to a position in advance of the machine to facilitate the removal of its contents.

50 In conjunction with these sliding work-boxes are preferably provided collapsible bundle racks adapted to be opened out from closed position to receive and support the work preparatory to stitching and to again 55 receive the work for convenience in bundling when removed from the work-box containing the stitched articles.

Secured upon the floor near the base of the column 1 are the floor-plates 54 each 60 provided with upright sockets 55 preferably open at the outer edge as well as the top with the sides connected together at the top by a cross-pin 56. Near the bottom of each socket 55 is mounted upon a pivotal pin 57 65 one end of a swinging post 58 upon whose

opposite end is pivotally mounted the forked depending lug 59 of the platform 60, the lug 59 having the cross-pin 61 which rests against the post 58 when the rack is opened out, as represented in the drawings, in which 70 condition the lower portion of the post 58 rests against the cross-pin 56. The rack may be readily closed when not in use, as represented in dotted lines at the left in Fig. 2, by tilting the plate 60 against the front 75 side of an adjacent work-box and swinging the post 58 in the same direction, thereby removing any obstruction which the rack would offer in the aisles between adjacent series of power-stands of the present type. 80

The upper end portion of each column 1 (Fig. 20) is contracted to afford a vertical bearing boss in which is adjustably secured by means of the set-screw 62 the cylindrical shank 63 of a bearing yoke 64 carrying the 85 center-screws 64' whose conical points enter similar cavities in the trunnions 65 extending oppositely from the central contracted portion 66 of a duplex transmitter-frame. This frame is shown formed at the opposite 90 ends with enlargements 67 having depending extensions 68 open at the bottom to accommodate transmission belts; and provided upon the upper side with hinged covers 69 for access to the interiors. By loosening the set-screw 62, the transmitter-frame supporting yoke 64 may be adjusted vertically or circularly, while such frame may be tilted upon its supporting center screws 64', so as to insure alinement with the 95 power-shaft 70 extending through the same: 100

The body portion 66 of the frame is bored out to receive the telescopically arranged bushings 71 and 72 secured in position by means of the set-screws 73 passing through 105 clearance apertures in the one and bearing upon the other (Fig. 6), the inner bushing affording a supporting bearing for the shaft 70. These bushings are formed with enlargements in their respective opposite 110 end portions to afford bearings upon each of which is fitted the hub 74 of one of the peripherally grooved belt-wheels 75 housed within the enlarged end portions 67, 68 of the transmitter-frame and adapted to rotate freely upon their respective bushings.

As shown more fully in my pending application Serial No. 85,535, filed March 21, 1916, the pulley 75 has a lateral brake-wheel extension 76 formed in its outer face 120 with a recess presenting a conical clutch face adapted for engagement by the conical face 77 of the clutch-disk 78 formed with the tubular hub 79. The clutch disk is shown provided with a diametrical slot 80 125 loosely embracing the correspondingly arranged driving arms 81 of a collar 82 secured by means of the set-screw 83 upon the shaft 70 within the hub 79 which is adapted to slide freely over the same in the 130

movement of the clutch-disk into and out of operative relation with the clutch element 76.

The contracted outer extremity of the hub 79 is adapted to be engaged by the thrust collar 84 embraced by and connected with the yoked arm 85 of a rock-lever having its hub portion 86 fulcrumed upon the stud 87 and provided with a depending cam-arm 88. The fulcrum-stud 87 is sustained by a rigid arm 89 extending from the cap 90 closing the adjacent end of the transmitter-frame and formed with a tubular boss 91 embracing the hubs 79 and 82 and the thrust collar 84, this boss being extended beyond the collar 84 and provided in its outer portion with the lateral cap 92 secured to the same by clamp-screws 93.

Fulcrumed upon a stud 94 sustained by a lug 95 extending from the cap 90 is a plural-armed lever comprising the angularly arranged arms 96, 97 and 98. The arm 96 sustains an endwise adjustable plate 99 carrying a roller-stud 100 adapted for engagement with the cam edge of the arm 88, and is maintained in lower and normally inoperative position by means of the spring 101 interposed between a socket in the arm 97 and the bottom of the fulcrum-sustaining arm 89. The arm 98 is apertured in the usual manner to receive the hooked upper end of the treadle-rod 102 extending downwardly through one of the lateral apertures 1' near the upper end of the column 1.

The rod 102 is connected at its lower end (Fig. 3) to the lateral crank-arm 103 of a transverse rock-shaft 104 journaled in a lateral bearing boss 105 at the foot of the column 1 and provided upon its outer end with a depending crank-arm 106. The crank-arm 106 is pivotally connected with one of the sections 107 of a pitman, these sections being adjustably secured together by means of the apertured block 108 and set-screws 109 in a manner well-known. The other of these pitman sections is connected with a crank-arm 110 depending from one of the trunnions 111 of the treadle-plate 112 sustained upon the supporting floor by means of the usual bearing brackets 113.

By employment of the described intermediate rock-shaft, the highly desirable housing of the treadle-rod 102 within the column may be maintained while providing for the advantageous lateral positioning of the treadle-plate to suit the requirements of individual operators, the compound pitman 107 readily accommodating itself to the spacing apart of the treadle-plate and rock-shaft 104.

Each of the belt-pulleys 75 is shown embraced by a transmission belt 114 which is led around the grooved pulley of the balance-wheel *c*, as represented in Figs. 1 and 2. These belts are shown inclosed each

within a divided tubular housing comprising the abutting sections 115 pivotally connected together at their upper ends by means of a fulcrum-pin 116 journaled within bearing apertures 117 (Fig. 7) formed in the transmitter-frame extensions 68. The inner housing section has pivotally connected thereto one end of a brace-rod 118 having its other end portion adjustably secured to the column 1 by means of a suitable clamp-screw 119. The outer housing section normally rests by gravity upon the complementary section.

When the sewing machine is to be removed or turned over for access to the parts beneath the bed-plate, the clamp-screw 119 may be loosened and the housing sections 115 swung apart for removal of the belt 114 from the balance-wheel pulley, after which the machine will be free to be moved as desired.

Figs. 21 and 22 represent a preferred form of belt connection, and housing therefor, between the transmitter pulley and the sewing machine. Upon a cross-pin 120 near the mouth of the transmitter-frame extension 68 is mounted the tubular spacing stud 121 of a swinging belt housing 122 of rectangular cross-section open at the rear side and carrying adjacent its forwardly open lower end the idler pulleys 123 mounted upon the cross-shaft 124. The housing 122 has near its upper end a lateral socket 125 containing a spring 126 interposed between the bottom of the same and a thrust lug 127 upon the frame section 68.

The two branches of the belt 114 are led from the pulley 75 downwardly beneath the idler pulleys 123 and around the pulley of the machine balance-wheel *c*, being maintained at a uniform tension by the retracting action of the spring 126 upon the housing 122. By this means, the housing will readily yield to permit the belt to be slipped over the balance-wheel when the machine is to be removed, or will permit the idlers to follow the movements of the machine when being tilted upon its supporting shelf, without disturbing the encircling belt.

As represented in Fig. 1, the adjacent faces of the transmitter-frames sustained by two adjacent columns are provided with angle-pieces 128 upon which is secured a connecting inverted T-beam 129. Secured upon this beam intermediate its ends by means of clamp-bolts 130 is a divided bracket-piece 131 having end flanges 132 to which are bolted the opposite flat sides 133 of shaft hangers each sustaining a bearing 134 for the power-shaft 70, each bearing being inclosed within a box 135. Embracing the edges of the hangers 133, in order to inclose a housing space between them, is a sheet-metal band 136 secured thereto at one end and provided at its opposite end with lateral lugs 137 130

adapted to enter notches in the upper edges of catch-bars 138 hinged at 139 and normally maintained in locking position by means of the bolts 140 and wing-nuts 141 5 or by other suitable means.

Fixed upon the shaft 70 intermediate the bearings 134 is a pulley 142 formed with a series of peripheral grooves entered by a corresponding series of convolutions of an 10 endless belt 143 passing over a similarly grooved pulley 144 upon a driving shaft 145 suitably mounted within the bearing of a hanger 146 attached to the ceiling in a manner well known. Rigidly sustained in 15 suitable lugs 147 of this hanger is the vertical guide-bar 148 upon which is slidingly fitted by a spline-and-groove connection the sleeve 149 provided with a lateral stud 150 carrying the grooved belt-wheel 151 enter- 20 ing a loop of the driving belt 143 extending from the opposite end grooves of the pulley 144. The sleeve 149 and wheel 151 are of such weight, or may be so weighted, that the driving belt 143 is given a uniform 25 tension of the required amount to produce the necessary driving impulse between the driving shaft 145 and the power-shaft 70. The wheel 151 thus constitutes an idler for maintaining the driving belt taut with a 30 uniform tension throughout the lengths of the pulleys 142 and 144.

Intermediate the adjacent transmitter casings, or between such casings and the hangers 133, the power-shaft 70 is housed 35 within the surrounding pipe sections 152 each having one end clamped within one of the bosses 91 and the other entering either another of said bosses or a boss 135' of a box 135. When extending between two of 40 the bosses 91, with its respective ends clamped therein, it is evident that these pipe sections 152 constitute tubular braces which aid in stiffening a structure comprising several of the described units each including 45 one of the columns 1; the columns embracing between them the hangers 133 being braced by means of the T-beam 129.

The structure is further stiffened by means 50 of the parallel stay-rods 153 having their end portions fitted within sockets formed in alined bosses 154 and 155 formed at opposite sides of the transmitter-frames 67 and their end caps 90 in which they are secured by means of set-screws 156. The end por- 55 tions of these rods constitute pintles upon which the tubular boss 69' of each hinged cover-plate is mounted and upon which it may be swung to give access to the bearings of the transmitter.

60 The stay-rods 153 afford convenient overhead supports for spool-stands of special construction which have been designed for employment in the present structure. These stands each comprise a plural-armed spider-frame 157, the arms being divergently ar-

ranged and each provided with a hooked extremity 157' adapted to engage one of the rods 153. Each of the frames 157 is formed at one side of its center with a socket 158 in which is secured by means of a set-screw 70 159 a vertical standard 160 having secured upon its lower end by a set-screw 161 the socket 162 of a cross-member 163 carrying a plurality of spool-holders 164 with vertical spool-pins 165 adapted to receive a com- 75 mercial thread-spool. The standard 160 is shown provided at its upper end (Figs. 1, 3, 17 and 18) with a cross-member 166 sus- taining guide-loops 167 corresponding in number with the spool-holders sustained by 80 the respective standard. The thread is led as usual from each spool upwardly through its respective guide-loop and thence to the sewing machine which it is designed to supply with thread. 85

From the foregoing description it will be seen that the present improvement pro- 90 vides a rigid structure occupying a minimum of floor space for a given number of sewing machines and absorbing the greater 95 portion of the vibration of individual ma- chines and also reducing the noise of opera- tion; that the space beneath the machines is wholly free from the driving mechanism so as to accommodate convenient work-recepta- 100 cles, to facilitate cleaning and prevent ac- cumulation of lint and other matter likely to cause or increase the danger of fire; that the work-holders or receptacles normally occupy a minimum of space and are capable 105 of assuming the most advantageous posi- tions both for reception and removal of the work; that the individual character of the machine-supporting shelves or tables and their detached relation facilitates the ac- commodation of circular articles requiring endlesseams, such as skirts; and that the various parts are so arranged and sustained as to provide for a maximum economy and convenience in the operation of the sewing 110 machines of a group.

It is obvious that the improvement is sus- 115 ceptible of very material modification, both in construction and arrangement of its sev- eral parts, within the scope of the invention; and that certain of its features may without departure from the invention be effectively employed without certain others of its fea- tures.

Having thus set forth the nature of the 120 invention, what I claim herein is:—

1. A sewing machine stand comprising a column carrying intermediate its head and foot a sewing machine supporting shelf or table and provided at its foot with a flange 125 extending at substantially right angles to the axis of the column, a floor-plate constructed separately from said column, fastening means for tiltably securing said flange to the floor-plate and positive means 130

for tiltably adjusting the said column on the floor plate.

2. A sewing machine stand comprising a hollow column carrying intermediate its head and foot a sewing machine shelf or table and provided at its foot with a flange and with an interior cross-member above the same, a floor-plate constructed separately from said column and provided with a centrally disposed aperture and with a surrounding series of seats upon its upper face, a bolt for connecting the centrally apertured portion of said floor-plate with the cross-member of said column, and adjusting bolts 10 tapped in the flange of said column and bearing upon the seats of the floor-plate.

3. A sewing machine stand comprising a shelf or table provided with sewing machine positioning means, and means for pivotally supporting the machine bed-plate and for shifting the same transversely of said positioning means to permit the machine to be tilted to expose its bottom without substantial bodily lateral displacement from 20 register with said positioning means.

4. A sewing machine stand comprising a shelf or table having an opening to receive the sewing machine bed-plate with means for supporting the machine in register with 30 said opening, and means for pivotally supporting the machine bed-plate and shifting the same across said opening to permit the machine to be tilted to expose its bottom without substantial bodily displacement from 35 register with said opening.

5. A sewing machine stand comprising a shelf or table provided with sewing machine positioning means, a swinging support connected to the machine bed-plate and having a fulcrum below the top of the table and intermediate component elements of 40 said positioning means and adapted for movement to carry its point of connection with the bed-plate across said fulcrum to permit the machine to be tilted for exposure of its bottom without substantial bodily lateral displacement from register with said 45 positioning means.

6. A sewing machine stand comprising a shelf or table having an opening to receive the sewing machine bed-plate with means for supporting the machine in register with said opening, a swinging support connected to the machine bed-plate and having a fulcrum intermediate the edges of said opening and adapted for movement to carry its point of connection with the bed-plate across said fulcrum to permit the machine to be tilted for exposure of its bottom with 55 out substantial bodily displacement from register with said opening.

7. A sewing machine stand comprising an upright column carrying intermediate its head and foot and extending mainly 60 from one side thereof a shelf or table sus-

taining a sewing machine bed-plate, and a swinging support connected to the machine bed-plate and having a fulcrum at the side of said connection farthest from said column and adapted for movement to carry 70 said point of connection across said fulcrum and farther from said column to permit the machine to be tilted toward but unobstructedly by said column.

8. A sewing machine stand comprising 75 an upright column carrying intermediate its head and foot and extending mainly from one side thereof a shelf or table having an opening and sustaining in register therewith a sewing machine bed-plate, a rock-shaft beneath said opening, laterally extending arms fixed to said rock-shaft and pivotally connected to said bed-plate, and means for turning said rock-shaft to shift 80 said arms across the same to facilitate the 85 tilting of the machine for access to the bottom thereof.

9. A sewing machine stand comprising an upright column carrying intermediate its head and foot and extending mainly 90 from one side thereof a shelf or table having an opening and sustaining in register therewith a sewing machine bed-plate, a rock-shaft beneath said opening, laterally extending arms fixed to said rock-shaft and 95 pivotally connected to said bed-plate, means for turning said rock-shaft to shift said arms across the same to facilitate the tilting of the machine for access to the bottom thereof, and means for locking said rock-shaft against turning. 100

10. A sewing machine stand comprising an upright column carrying intermediate its head and foot and extending mainly from one side thereof a shelf or table having an 105 opening and sustaining in register therewith a sewing machine bed-plate, a rock-shaft beneath said opening, sustaining means for shifting said bed-plate crosswise of said opening, fastening means for maintaining the sewing machine in operative position, and a drip-pan pivotally sustained upon said rock shaft and maintained in operative position beneath said opening by 110 said fastening means. 115

11. A sewing machine stand comprising an upright column carrying intermediate its head and foot and extending mainly from one side thereof a shelf or table having an opening and sustaining in register 120 therewith a sewing machine bed-plate, a rock-shaft beneath said opening, sustaining means for shifting said bed-plate crosswise of said opening, fastening means for maintaining the sewing machine in operative position, and a drip-pan formed with flanges having hooked arms embracing said rock-shaft and engaged also by said fastening means for maintaining it in operative 125 position beneath said opening. 130

12. A sewing machine stand comprising an upright column carrying intermediate its head and foot and extending mainly from one side thereof a shelf or table having an opening and sustaining in register therewith a sewing machine bed-plate, a rock-shaft beneath said opening, sustaining means for shifting said bed-plate crosswise of said opening, a clamp-bolt applied to 5 said shelf and having a head engaging said bed-plate for maintaining it firmly seated upon the shelf, and a drip-pan formed with flanges having hooked arms embracing said rock-shaft and a forked lug embracing said 10 clamp-bolt by which it is clamped to said shelf. 60
13. A sewing machine stand comprising a support having a shelf with an opening therein, a sewing machine supported in said 0 opening and having a pivotal mounting, and means whereby the pivotal mounting may be disposed at either side of the opening. 65
14. A sewing machine stand comprising a support having a shelf with an opening therein, a sewing machine having a pivotal mounting at one side of the opening, and means whereby the pivotal mounting may be moved from one side of the opening to 10 the other while the machine is being swung on its pivot. 70
15. A sewing machine stand comprising a support having a shelf with an opening therein, a sewing machine supported in said 35 opening, and means whereby the machine may be tilted from a vertical to a horizontal position above the opening while maintaining it substantially in register with said opening. 75
16. A sewing machine stand comprising a column, a shelf secured thereto at a point below its top, a sewing machine having a pivotal mounting on said shelf adjacent said column, and means for moving said mounting away from said column when the machine is tilted on its pivot, whereby interference with said column is avoided. 80
17. A sewing machine stand comprising a support having a shelf with an opening 50 therein, a sewing machine supported in said opening, a pivotal mounting for said machine, and means whereby the pivotal mounting may be shifted to allow the machine to be tilted from a vertical to a substantially horizontal position while maintaining it substantially in register with said opening. 85
18. A sewing machine stand comprising an upright column sustaining intermediate its head and foot a sewing machine supporting shelf and below it a transverse rail, and a work-receptacle movably sustained upon said rail, disposed beneath said shelf and adapted to be shifted laterally for exposure of the shelf. 90
19. A sewing machine stand comprising an upright column sustaining intermediate its head and foot a sewing machine supporting shelf and below it a transverse rail, and a work-receptacle disposed below said shelf 65 and slidably mounted at the side adjacent the column upon said rail and adapted to be shifted laterally for exposure forwardly and rearwardly of the shelf, said column being provided beneath the rail with a lateral support against which the lower portion of the work-receptacle rests. 70
20. A sewing machine stand comprising an upright column carrying intermediate its head and foot a sewing machine shelf or 10 table having an opening to receive a sewing machine bed-plate, a rock-shaft sustained by said shelf or table beneath said opening and carrying a normally depending knee-lever for operation upon an element of the 80 sewing machine, and detaining means for temporarily holding the lever elevated in inoperative position when swung upwardly for the purpose. 85
21. A sewing machine stand comprising an upright column carrying intermediate its head and foot a sewing machine shelf or table having an opening to receive a sewing machine bed-plate and an adjacent depending rib or flange formed with a lateral 90 detent notch, a rock-shaft sustained by said shelf or table beneath said opening and carrying a normally depending knee-lever for operation upon an element of the sewing machine, and a knee-plate fixed to said lever with an edge adapted to spring into said detent notch of the shelf-flange by which it is yieldingly detained when the knee-lever is raised into inoperative position. 95
22. A sewing machine stand comprising an upright column sustaining intermediate its head and foot a sewing machine supporting shelf, a work-receptacle, and means whereby the work-receptacle is movably 100 sustained by said column disposed beneath said shelf and adapted to be shifted laterally on its sustaining means for exposure forwardly and rearwardly of the shelf. 105
- In testimony whereof I have signed my name to this specification. 110

ALBERT H. DE VOE.

It is hereby certified that in Letters Patent No. 1,347,840, granted July 27, 1920, upon the application of Albert H. De Voe, of Westfield, New Jersey, for an improvement in "Power-Stands for Sewing-Machines," an error appears in the printed specification requiring correction as follows: Page 7, line 64, claim 18, after the word "exposure" insert the words *forwardly and rearwardly*; and that the said Letters Patent should be read with this correction therein that the same may conform to the record of the case in the Patent Office.

Signed and sealed this 24th day of August, A. D., 1920.

[SEAL.]

M. H. COULSTON,

Acting Commissioner of Patents

Cl. 45—27.
